ADHESIVE COATED METALLIC FILM

William Frederick Grupe, Lyndhurst, N. J., assignor to Peerless Roll Leaf Co., Inc., Union City, N. J., a corporation of New York

Application May 14, 1934, Serial No. 725,583

13 Claims. (Cl. 206—71)

This invention relates to fragile metal film reinforced by a non-metallic, tough coating. In its most preferred form, the invention is directed to metal film, and particularly gold film, reinforced by a hardened and tough coating of adhesive material applied to one face thereof.

Beaten gold or gold in a form comparable to beaten gold, has a thickness approximating one two-hundred-and-fifty-thousandths of an inch, and therefore readily subject to being torn or otherwise spoiled when handled manually. My invention, by virtue of the applied coating enables film or sheet gold of the magnitude of the thickness of beaten gold to be handled substantially freely without the hazard of being torn or otherwise spoiled. The coating material also serves, particularly for low carat leaf, to check tarnishing.

Advantageously, the coating material is an adhesive, applicable in the use of the gold film or sheets in the arts, as in sign painting, china and other decorating arts, and the like.

My invention includes further the utilization of a "book", preferably having its normally lower cover stiff or but semi-flexible, and sheets of coated gold freely disposed between the leaves of the "book". Desirably, the dull or less highly finished face of the gold sheets, that is, the faces bearing the coating material, are positioned between the leaves of the book to face upward. The top cover is flexible, or may be absent. Such "book" facilitates the application of the individual gold sheets, as in sign painting and the like, the operator grasping the stiff or semi-flexible cover as a handle and the "book" as a whole as a pad.

My invention is particularly applicable to the utilization of electrolytically derived film of gold, its alloys and the like, an established production of which embodies the use of a silver cathode upon which the film is deposited, the resulting composite product being subjected to a bath containing nitric acid, for the removal of the silver cathode, and the mounting of the thus derived film of gold or the like upon a carrier of paper or like medium. As is set out in my U. S. Patent #1,731,415, granted to me on Oct. 15, 1929, film of gold, its alloys and the like are obtained of a length materially greater than that of beaten gold, the length of beaten gold averaging not greater than six or seven inches.

Further features and objects of my invention will be more fully understood from the following detail description and the accompanying drawing, in which

Fig. 1 is a transverse sectional view, largely diagrammatic, through a film of gold or section of gold film, bearing a coating or other applied material on a face, the stated parts being greatly exaggerated in individual and relative dimensions. 5

Fig. 2 is a perspective view of a "book" of sections or plates of gold film individually embodying my invention.

Referring to Fig. 1, a length, section, sheet or 10 film of gold is indicated at 10. The highly finished face of the gold is denoted at 10a, and its relatively dull face at 10b. The coating or layer of applied material 11 is shown applied to the relatively dull face 10b of the gold film. 15

The coating or material is applied to the gold film in any suitable manner.

A preferred manner of coating or applying material to gold film is as follows:

The film of gold is produced in a status of 20 mechanical attachment to a suitable carrier strip. As one means of obtaining the same, a strip of indefinite length of silver is passed through a bath containing a solution of gold, and gold electrolytically deposited upon the silver strip serving 25 as a cathode, the thickness of the deposit being regulated by the speed of travel of the cathode through the bath, the control of the electrical circuit, and other factors well-known to those skilled in the art, reference being had to the 30 Demel U. S. Patents #1,512,825, dated Oct. 21st, 1924 and #1,513,696, dated Oct. 28th, 1924.

The resulting silver carrier gold film strip is then treated for the removal of the silver, as by passing the same through a bath of nitric acid, 35 and then through a bath of water for the removal of nitric acid, and then through a bath of other medium for removal of water and/or other materials foreign to gold.

Pursuant to my invention, the thus freed film 40 of gold is then passed through, and preferably upon the surface of, a bath containing the sizing and/or other material with which film is to be coated.

The sizing may be of the water base type, such 45 as animal glue, gum arabic, etc. The base of the sizing may be alcohol, as in shellac, manila copal, resin including rosin, etc. The sizing may have a hydrocarbon as a base, such as rubber or latex dissolved in benzine, gasoline, etc. Should a 50 water base sizing be employed, the gold film may be passed from the water bath employed in the removal of the silver carrier strip directly to and upon the surface of the bath of the water base sizing, reliance being had of the surface 55

tension effect. When an alcohol or hydrocarbon base sizing is employed, the water residual from the water bath, is removed in any suitable manner prior to passing the gold film to the bath of the alcohol or hydrocarbon base sizing.

- 8 Sizing of the character above described, when applied to one face of the film and allowed to harden, possesses toughness which acts as a reinforcement for the film. The coating of sizing 10 applied should be of sufficient strength, attained by the particular attributes of the sizing employed and/or by thickness of coating, to in itself adequately reinforce the film for ordinary handling assuming the film to be otherwise unsupported.
- 15 Other suitable material may be applied to the gold film in like manner.

The resulting strip or indefinite length of gold film may then be cut to suitable size, or may be wound as a roll.

- 20 By the stated or equivalent electrolytic production of gold film, of such length as may be desired, the face of the film adjacent the silver or other cathode carrier is the relatively dull face, indicated at 10b in Fig. 1. The face 10b, 25 accordingly, is the lower face of the gold film when passed through or upon the nitric acid bath serving as the silver removing medium, thus enabling the thus released gold film to be continued in its same position to the adhesive or 30 other coating bath.

The thus derived individual cut sheets or film of gold are preferably stored in a "book" formed of a stiff or semi-flexible lower back 12, leaves 13, of suitable thin paper, an upper flexible cover 35 14, and bound at the back 15. The leaves 13 may be face-calendered and/or dusted or coated with rouge to be rendered non-adhesive, or treated with oil or otherwise to be rendered adhesive relative to the gold film or sheets inserted between the leaves 13.

40 The respective films or sheets of gold may all be inserted with its coated face 10b disposed upward, that is to say, directed opposite to the stiff or semi-flexible cover 12, or the respective films 45 or sheets may be all inserted with their coated faces positioned downward, either arrangement serving to identify the high finish face of the gold films or sheets by their positions relative to the rear or lower cover of the "book".

50 Such book, in addition to its function as a carriage and dispensing medium, serves also as a pressure pad device as, for example, for sign painting, the painter after preparing the surface of the glass or other material to be lettered or 55 otherwise embellished, opens up his "book", to expose the uppermost film or sheet of gold, and successively the succeeding films or sheets, upon turning over the successive pages of the "book".

If desired, the upper cover 14 may be omitted. 60 Whether with or without the cover 14, the bulk of the "book", after exposing the uppermost sheet or leaf of gold, may be employed by the operator as a pad in applying such uppermost leaf to the work, such as the painting of a sign, etc.

65 The use of the "book" having all of its contained gold sheets or leaf positioned with their highly finished faces upward, applies in such instances of use, as in a sign or other embellishment viewed through glass or other transparent 70 medium, in which circumstance the rear face of the glass or other transparent medium is treated with sizing and the gold applied with its highly finished face in contact with the sizing.

75 For certain commercial uses, the coating material, which may or may not be of adhesive

character, is dyed of a predetermined color, such as green, lemon or light yellow, red, etc., to impart such color to the gold film or sheet affected by the transparency of the film or sheet arising from its extreme thinness, i. e., of the magnitude 5 of beaten gold.

Whereas I have described my invention by reference to specific forms thereof, it will be understood that many changes and modifications may be made without departing from the spirit 10 of the invention.

I claim:

1. A fragile metal film having one face substantially coextensively coated with a non-metallic hardened and tough reinforcing coating 15 material of sufficient strength to in itself adequately reinforce the said metal film for ordinary handling, said film being otherwise unsupported.

2. A fragile metal film having one face substantially coextensively coated with a hardened 20 and tough adhesive sizing of sufficient strength to in itself adequately reinforce the said metal film for ordinary handling, said coated face being exposed for suitable adhesion to a supporting surface.

25 3. A fragile metal film as recited in claim 2 wherein the stated adhesive sizing is artificially colored.

4. A fragile metal film having one face substantially coextensively coated with a hardened 30 and tough, resinous adhesive sizing of sufficient strength to in itself adequately reinforce the said metal film for ordinary handling, said coated face being exposed for suitable adhesion to a supporting surface.

5. A fragile metal film as recited in claim 4 wherein the stated resinous adhesive sizing is artificially colored.

6. A fragile gold film having a thickness comparable to that of beaten gold and having one 40 face substantially coextensively coated with a hardened and tough adhesive sizing of sufficient strength to in itself adequately reinforce the said gold film for ordinary handling, said coated face being exposed for suitable adhesion to a supporting 45 surface.

7. A fragile metal film as recited in claim 6 wherein the stated adhesive sizing is artificially colored.

8. An electrolytically deposited fragile film of 50 gold having a thickness comparable to that of beaten gold and having one face substantially coextensively coated with a hardened and tough adhesive sizing of sufficient strength to in itself adequately reinforce the said gold film for ordinary handling, said coated face being exposed for suitable adhesion to a supporting surface.

9. A strip of gold film having a thickness comparable to that of beaten gold and an integrally continuous length materially greater than the 60 greatest possible integrally continuous length of beaten gold, said strip having one face substantially coextensively coated with a hardened and tough adhesive sizing of sufficient strength to in itself adequately reinforce the said gold film for 65 ordinary handling, said coated face being exposed for suitable adhesion to a supporting surface.

10. A fragile gold film as recited in claim 9 wherein the stated adhesive sizing is artificially colored.

70 11. A metal-leaf applying book comprising a plurality of metal-leaf sheets, each consisting solely of a fragile metal film having one face substantially coextensively coated with a hardened and tough adhesive sizing of sufficient strength 75

to in itself adequately reinforce the said metal film for ordinary handling, said coated face being exposed for suitable adhesion to a supporting surface, and said book further comprising separating-sheets interposed between mutually adjacent metal-leaf sheets.

5 12. A fragile gold film as recited in claim 8 wherein the stated adhesive sizing is artificially colored.

10 13. A gold-leaf applying book comprising a plurality of gold-leaf sheets each consisting solely

of a fragile gold film having one face substantially coextensively coated with a hardened and tough adhesive sizing of sufficient strength to in itself adequately reinforce the said gold film for ordinary handling, said coated face being exposed for suitable adhesion to a supporting surface, and said book further comprising separating-sheets interposed between immediately adjacent gold-leaf sheets.

5
